UNITED STATES PATENT OFFICE.

MILTON C. STERN, OF DAYTON, OHIO, ASSIGNOR TO THE EGRY REGISTER COMPANY,
OF DAYTON, OHIO, A CORPORATION OF OHIO.

AUTOGRAPHIC REGISTER.

1,378,628.

Specification of Letters Patent. Patented May 17, 1921.

Application filed July 2, 1920. Serial No. 393,624.

To all whom it may concern:

Be it known that I, MILTON C. STERN, a citizen of the United States, residing at Dayton, in the county of Montgomery and State of Ohio, have invented certain new and useful Improvements in Autographic Registers, of which the following is a specification, reference being had therein to the accompanying drawing.

10 This invention relates to improvements in autographic registers.

The particular feature which constitutes my invention comprises the means for guiding the strips of paper as they pass out of contact with the feeding devices by which the paper is advanced through the machine after each sale is recorded.

My object is to engage the oncoming strips of paper, just as they are leaving their feeding relation with the feeding devices to prevent them from feeding downwardly and guide them sharply upwardly as they travel rearwardly. The effect of so directing the strips is to position them so that they can more readily be taken hold of by the hand and drawn against the tear-off edge of the machine. By so guiding them they are presented toward the tear-off edge even before they are taken hold of. All this will appear 30 more fully hereinafter.

In the accompanying drawings:

Figure 1 is a longitudinal sectional view of an autographic register with my improvements embodied therein;

35 Fig. 2 is a detailed perspective view of my guide bar mounted on the section of the top plate which carries it;

Fig. 3 is a longitudinal, vertical section, in detail, on an enlarged scale; and

40 Fig. 4 is a perspective view of a portion of the lid of the machine and of the top plate which carries my guide bar.

In Fig. 1 I have illustrated any approved type of autographic register comprising a 45 general casing 1, with a fixed end plate 2 and a hinged end plate 3, as also with the lid 4 hinged at 5 and the tablet plate 6 located under the opening 7 in the lid.

This tablet plate 6 supports the several 50 sheets of paper, between each two of which there is used in practice a carbon sheet. In this illustration I have shown two paper strips 8 each run off of a paper roll 9, and guided by supporting rolls 10. These strips 55 are fed in any approved manner, so far as

my invention is concerned, but in the illustration I have shown that type of paper feeding mechanism comprised in the co-pending application of August A. Wimmers, filed Feb. 13th, 1920, Ser. No. 358,557, and assigned to The Egry Register Company, my assignee herein. For this reason, I will not describe this paper feeding mechanism further than to say that it is such as to coöperate with perforations in the two lateral margins of the strips or sheets of paper, so as to advance the sheets a given distance upon each turn of the operating crank.

Coming now to my particular improvement, the numeral 11 designates one section 70 of top plate of the casing. This section is adapted to slide in the sides of the casing, as suggested at 12. It carries my improved paper guiding bar 13, which may be integral with the plate or otherwise attached thereto. It will be observed that this bar at its right hand edge, as shown in Fig. 1, stands just where the feeding devices lose contact with the paper strips. The strips are in this manner delivered to and upon the 80 guide bar. The bar rises sharply from this right hand edge 14 to its extreme margin 15 and the paper is prevented from feeding downwardly and gradually but pronouncedly directed upwardly, as seen in Fig. 1, 85 and as will be understood to be the case by glancing at Fig. 3. The top surface of the guide bar may be concaved, as shown, or otherwise.

The paper having been directed in the 90 course described and indicated, it is readily taken hold of, and without having to fumble for it or lift it, so that the store clerk can instantly grasp it and swing it farther upward and somewhat backward until it makes 95 contact with the tear-off edge 16 formed on the extreme end of the hinged lid 4. Against this edge the paper is quickly drawn upward and laterally to tear it off.

This position of the paper is shown in 100 dotted lines in Fig. 3, it being understood that the paper has been fed through the machine far enough to present beyond the tear-off edge one section or writing portion. The paper is printed in separate forms, one 105 after another, each form constituting a section upon which the sales memoranda are written.

By observing Fig. 4, it will be seen that the plate 11, which carries the guide bar, 110

performs the incidental office of engaging a lock hook 17 on the lid 4 so as to lock the lid down. The plate, when slid into normal position, rests over the hook 17, as shown at 18.

5. It will be understood that any type of paper feeding mechanism may be employed, though I prefer that illustrated in Fig. 1.

In the manufacture of these autographic registers by my assignee, my improved paper 10 guide bar has been found to be easily and cheaply made, while in practice among users in the trade it has proved to be useful and acceptable, as it presents the paper in a most convenient position for being taken hold of 15 and then subjected to the tear-off operation.

Having thus fully described my invention, what I claim as new and desire to secure by Letters Patent, is:—

1. In an autographic register, the combination with paper strip feeding devices and 20 a casing with a lid in two sections, one section having a tear-off edge, and the other section having a paper guide bar having one edge located in such proximity to the feeding device that the paper strips enter upon 25 the bar and having its upper surface sharply inclined to lift the paper toward the tear-off edge.

2. In an autographic register, the combination with paper strip feeding devices, 30 and a casing having a tear-off edge above

the same, of a detachable top plate with a paper guide bar having one edge and its adjacent upper surface near to and about on a level with the feeding devices as they move past the bar, and having its upper surface sharply inclined to lift the paper toward the tear-off edge. 35

3. In an autographic register, a casing having a top plate in a plurality of sections, 40 one section of the top plate having a paper guide bar secured thereto, one edge of the bar being thin to lower the adjacent part of the top surface, and the other edge of the bar thick to elevate that part of the top surface, so that the top surface as a whole inclines sharply from one edge to the other. 45

4. In an autographic register, the combination with a lid having lock hooks and a section of the top plate adapted to be positioned over said hooks and having a paper guide bar mounted thereon and occupying a position within the portions of the plate which engage the hooks, said bar having one edge low and the other edge high, the upper surface extending from the low edge to the high edge and constituting a sharp incline. 50

In testimony whereof, I affix my signature.

MILTON C. STERN.
